DESIGN FOR A MOTION PICTURE CAMERA MOTOR-DRIVE CASING

Walter H. Bach, Los Angeles, Calif., assignor to
E. M. Berndt Corporation, Los Angeles, Calif.

Application May 1, 1942, Serial No. 106,772

Term of patent 14 years

To all whom it may concern:

Be it known that I, Walter H. Bach, a citizen of the United States, residing at Los Angeles, in the county of Los Angeles and the State of California, have invented a new, original, and ornamental Design for a Motion Picture Camera Motor-Drive Casing, of which the following is a specification, reference being had to the accompanying drawing, forming a part thereof.

In the drawing:

Fig. 1 is a perspective view of a motion picture

camera motor-drive casing showing the front and one side of the casing and illustrating my new design.

Fig. 2 is a perspective view of the motion picture camera motor-drive casing shown in Fig. 1, but illustrating the back and the opposite side of the casing from that shown in Fig. 1.

I claim:

The ornamental design for a motion picture camera motor-drive casing, as shown.

WALTER H. BACH.
